COUPLER SHANK AND YOKE CONNECTION

Ernest H. Schmidt, Cleveland Heights, Ohio, assignor to National Malleable and Steel Castings Company, Cleveland, Ohio, a corporation of Ohio

Application September 21, 1927
Serial No. 220,920

9 Claims. (Cl. 213—71)

My invention relates to coupler shank and yoke connections, and comprises a structure which permits radial movement of the coupler relative to the yoke in such a way as to give equalized pulling and buffing. My improved construction also provides means by which the coupler and yoke may be secured together without the use of keys or rivets and which may be readily assembled and disassembled. My invention also comprises various features which I shall hereinafter describe and claim.

In the accompanying drawings Fig. 1 is a horizontal section of the rear end of a coupler and forward end of a yoke embodying my invention; Fig. 2 is a vertical longitudinal section thereof on lines II—II of Fig. 1; Fig. 3 is a vertical transverse section on lines III—III of Fig. 2; and Fig. 4 is a vertical transverse section on lines IV—IV of Fig. 2.

Referring more specifically to the drawings, A indicates the coupler shank and B the yoke. The arms 2 of the yoke at their forward ends are connected by the webs or walls 3 to form a hood. The arms 2 on their inner faces in the region of the hood have recesses 4 to receive the retaining members 5. The forward and rear walls 6 and 7 of the recesses 4 are arcuate in form and the adjacent forward faces 8 of the retaining members 5 are curved correspondingly to the walls 6 to permit lateral angling of the coupler relative to the yoke. The retaining members 5 have rearwardly facing shoulders 9 abutting against forward faces 10 of the coupler butt or liner block extensions 11. At each side of the coupler butt the retaining members 5 are flanged over at 12, as is shown in Figs. 1 and 3, to hold the retaining members 5 in position on the coupler butt and cause them to angle or rotate with the coupler relative to the yoke. When the coupler angles to one side or the other, the flanges 12 on that side will enter the aperture 13 in the adjacent side wall 3 of the yoke hood.

It will be seen that the distance between the inner edge of one of the yoke gibs 14 and the adjacent surface 15 of the coupler shank A is equal to or greater than the total height of the retaining member to permit the assembly of the parts, as will later be described.

In order to provide for radial buffing the rear end of the coupler preferably terminates in the form of a concave face 16 which may be formed upon a separate supporting member 17, secured to the rear end of the coupler shank by means of a projection 18 inserted through the rear aperture 19 which is usually provided at the rear end

of the coupler butt. The projection 18 has a vertical opening 20 through it, which when the parts are in place is in register with the rear vertically extending rivet hole 21 of the coupler butt. The member 17 is then secured in the coupler butt by driving a pin or piece of pipe 22 through the rivet hole 21 and through the opening 20 in the extension 18, thus locking the member 17 rigidly to the rear face of the coupler shank. Against the concave face 16 of the member 17 fits the forwardly facing convex face 23 of the buffing piece 24. The rear face 25 of the buffing piece 24 is flat and is intended to engage with a draft gear, the forward element of which is indicated at 26. The buffing piece 24 is secured against the rear face 16 of the member 17 by means of a dowel 27 which extends through an elongated aperture 28 in the buffing piece 24, upon which the buffing piece is held by means of a washer 29, over which the dowel 27 is riveted. The elongated aperture 28 in the buffing piece 24 permits the buffing piece 24 to swing laterally relative to the coupler shank and the supporting member 17, so that the buffing piece 24 can always bear flat against the front follower 26 regardless of the angular position of the shank A. The overall dimension of the coupler butt may be varied by increasing or decreasing the thickness of the supporting member 17 and the buffing piece 24, or either of them, to compensate for use in connection with draft gears of varying construction.

In assembling my improved mechanism the buffing piece 24 is secured upon the coupler butt by means of its supporting piece 17. When the coupler A is assembled with the yoke B, before either is placed in position in the car. To effect this the retaining members 5 are laid against the upper and lower surfaces of the shank forward of the coupler butt extensions 11. The coupler and the members 5 with it are then slid into the forward end of the yoke hood until the shoulders or faces 10 on the coupler butt come opposite the rear surfaces 7 of the recesses 4 in the yoke. This brings the lower retaining member 5 in position to drop down into the bottom recess 4, and then the upper retaining member is lifted into the upper recess in the position shown in Fig. 2 of the drawings. The coupler is then pulled forward until its surfaces 10 come up against the shoulders 9 of the retainers. The subsequent insertion of the draft gear 26 in place in the yoke locks the entire arrangement together.

When the parts have been placed in position

on the car it will be seen that the coupler is free when under draft to angle laterally or move radially relative to the yoke, by reason of the arc-shaped bearing of the forward faces 8 of 5 the retaining members 5 upon the correspondingly shaped faces 6 on the yoke gibs 14. It is desirable to construct the pulling surfaces 6 on the yoke on a radius of curvature so that as the coupler butt rotates about the center of 10 such radius the rear corner of the butt or the attached parts will come into contact with the rear portion of the inner face of the side wall 3 of the yoke hood approximately at the same time that the shank will engage the forward 15 end of the opposite side wall of the hood, as is shown in broken lines in Fig. 1. It will therefore be seen that the maximum amount of lateral angling or radial movement between coupler and yoke is provided. This arrangement also 20 provides for the maximum amount of radial movement under buff, and in both draft and buff gives a full and equalized bearing between coupler and yoke.

The terms and expressions which I have employed are used as terms of description and not of limitation, and I have no intention, in the use of such terms and expressions, of excluding any mechanical equivalents of the features shown and described, or portions thereof, but recognize 30 that various structural modifications are possible within the scope of the invention claimed.

What I claim is:

1. A coupler shank and yoke connection comprising a vertical plane yoke having vertically extending recesses in the inner faces of its arms; retaining members seating in said recesses and having an arc-shaped pulling engagement with the yoke, said retaining members being angularly movable at all times with said coupler and being longitudinally movable with the coupler in draft and relative thereto in buffing.

2. A coupler shank and yoke connection comprising a vertical plane yoke having vertically extending recesses in the inner faces of its arms; retaining members seating in said recesses and having an arc-shaped engagement with the yoke, said retaining members being movable with the coupler relative to the yoke during angling and movable with the yoke relative to the coupler during buffing.

3. A coupler shank and yoke connection comprising a vertical plane yoke having vertically extending recesses in the inner faces of its arms; retaining members seating in said recesses and having an arc-shaped engagement with the yoke, a draft gear, and a buffing segment supported on the rear end of the coupler butt and capable of radial movement relative thereto engaging an element of the draft gear, said retaining members and segment being so constructed and arranged as to provide a free sliding movement in the angling of the coupler thereby facilitating such angling in the normal position of the parts.

4. A coupler shank and yoke connection comprising a vertical plane yoke having arc-shaped pulling faces; a coupler butt; retaining members having faces engaging said pulling faces and said coupler butt, said retainers being held while in operative position from longitudinal movement 65 away from said arc-shaped faces by vertical faces on the yoke.

5. A coupler shank and yoke connection comprising a hooded yoke having a space between its yoke arms of slightly greater extent than the over-all height of the coupler butt; retaining members,

said hood also having recesses for the reception of said retaining members, said retaining members being of a height less than the distance from the top of the shank to the bottom of the adjacent yoke gib to permit the insertion of the retaining members with the coupler through the forward side of the hood into said recesses and there form an operative engagement between the coupler and yoke, the engagement of the members and the yoke during draft being arc-shaped, and means to cause the retaining members to move radially with the coupler relative to the yoke at all times.

6. In mechanism of the class described, a coupler having a shank, a yoke adapted to receive said shank, a retainer between said shank and yoke, said shank being movable longitudinally relative to said retainer, means for preventing relative longitudinal movement between said retainer and yoke and interlocking means for causing said retainer to angle at all times with said shank.

7. Buff transmitting means insertable between a coupler butt, having a flat buffing face, and a draft gear, comprising a plurality of interconnected members, each of said members having a flat surface engaging said butt and draft gear respectively, each of said members also having an arc shaped face cooperating with a complementary shaped face on the other of said members, and means for connecting said members including a projection on one member and an elongated slot on the other member to slidably receive said projection.

8. In a coupler and yoke connection, the combination with a yoke having top and bottom arms and a hood portion defined by spaced side walls and spaced top and bottom walls, said spaced top and bottom walls having opposed seats, each seat having a curved transverse front end wall, and said side walls having openings communicating with said seats; of a coupler having top and bottom transverse shoulders on the butt portion of the shank thereof, said coupler butt corresponding in height to the spacing between the top and bottom arms of the yoke; and a locking block disposed within each of said seats, each block having a curved transverse front end face bearing on and having shouldered engagement with the curved front end wall of the corresponding seat, each block also having a pocket in which the shouldered portion of the coupler butt is seated, said pocket having spaced side walls overlapping the side faces of the coupler butt to lock said block against lateral displacement with respect to the coupler butt, and a transverse front wall cooperating with the corresponding shoulder of the coupler butt to limit outward movement of the coupler with respect to the locking block and yoke, said coupler being movable relatively to the locking blocks inwardly of the yoke.

9. A coupler shank and yoke connection comprising a coupler, a yoke and a draft gear; and means secured to the coupler for effecting equalized distribution of the force between the coupler and draft gear in buff, said means comprising a supporting member secured to the coupler having an arc-shaped rear face, a buffing block having a complementary arc-shaped face in engagement therewith, and means for flexibly securing the buffing block with its arc-shaped face in engagement with the arc-shaped face of the supporting member whereby the buffing block may be shifted relative to the coupler.
